[57] CLAIM

The ornamental design for a water closet valve, as shown and described.

DESCRIPTION

FIG. 1 is a side elevational view of a water closet valve showing my new design, the other sides being the same as the side shown;

FIG. 2 is a top plan view thereof;

FIG. 3 is a bottom plan view thereof; and

FIG. 4 is a cross-sectional view taken on line 4—4 of FIG. 2.

FIG. 2

FIG. 1

FIG. 3
